(57) **CLAIM**

The ornamental design for a computer tomography measuring device, as shown and described.

DESCRIPTION

FIG. 1 is a perspective view of a computer tomography measuring device showing the ornamental design of the present invention;

FIG. 2 is a first side view of the computer tomography measuring device of FIG. 1;

FIG. 3 is a top view of the computer tomography measuring device of FIG. 1;

FIG. 4 is an opposite side view of the computer tomography measuring device of FIG. 1;

FIG. 5 is a bottom view of the computer tomography measuring device of FIG. 1;

FIG. 6 is a front view of the computer tomography measuring device of FIG. 1; and,

FIG. 7 is a rear view of the computer tomography measuring device of FIG. 1.

The broken lines included in FIGS. 1-7 for the purpose of illustrating portions of the computer tomography measuring device form no part of the claimed design.
